(57) **CLAIM**

The ornamental design for a fishing reel, as shown and described.

DESCRIPTION

FIG. 1 is a first perspective view of a fishing reel in accordance with my new design.

FIG. 2 is a second perspective view of the fishing reel illustrated in FIG. 1.

FIG. 3 is a third perspective view of the fishing reel illustrated in FIG. 1.

FIG. 4 is a front elevational view of the fishing reel illustrated in FIG. 1.

FIG. 5 is a rear elevational view of the fishing reel illustrated in FIG. 1.

FIG. 6 is a top plan view of the fishing reel illustrated in FIG. 1.

FIG. 7 is a bottom plan view of the fishing reel illustrated in FIG. 1.

FIG. 8 is a first side elevational view of the fishing reel illustrated in FIG. 1; and,

FIG. 9 is a second side elevational view of the fishing reel illustrated in FIG. 1.

In the drawings, the broken line illustration in the drawings is not part of the claimed design. In other words, the broken line portion of the fishing reel does not form part of the claimed design.

1 Claim, 6 Drawing Sheets
